UNITED STATES PATENT OFFICE

HUGO STEIN, OF VIENNA, AUSTRIA

FOUNTAIN PEN

Application filed October 19, 1928, Serial No. 313,603, and in Austria December 8, 1927.

This invention relates to self-filling fountain pens and it refers particularly to pens having an ink reservoir formed of an elastic material, for example, rubber, which is 5 capable of being twisted in either direction from the position of rest for the purpose of filling the pen and then resumes its normal position.

According to this invention means are 10 provided to limit the number of turns of the member serving for twisting the reservoir in either direction. The shortening of the axial length of the reservoir, caused by twisting it, is made use of for limiting the 15 number of turns.

The appended drawing shows by way of example two forms of the invention.

Fig. 1 is a view partly in section of the fountain pen with the elastic ink reservoir 20 in its normal position.

Fig. 2 is a view partly in section of the fountain pen with the ink reservoir twisted.

Fig. 3 is a view partly in section of a modification.

According to Fig. 1 the ink reservoir 2, which is formed of rubber, is disposed inside the outer shell or case 1 holding the plug 9 which carries the nib. The reservoir is connected at one end to the plug and at the 30 other end is closed by a stopper 3.

A knob 5 is provided, which knob is rotatable in relation to the shell, but cannot otherwise be displaced. In a recess 6 in the knob 5 lies a pin 4 which is connected firmly 35 to the stopper 3. The recess 6 and pin 4 are of square, polygonal or other unround cross sectional outline, so that the pin 4 can be moved axially in relation to the knob 5, but is carried round by the latter when 40 turned. The stopper 3 carries a projection 7 which can co-operate with a stop 8 fitted to the inner wall of the shell 2.

To fill the reservoir 2 with ink it is twisted in one direction or the other, so that if it is turned to the right for example it takes the position shown in Fig. 2. If the 45 knob 5 be turned the pin 4 is carried round with it, thus twisting the elastic reservoir 2. In the form of the invention shown this reservoir is rigidly connected only to the

plug 9 holding the nib, and therefore when twisted as stated above it contracts in such a way that its opposite end descends slightly. At the same time the pin 4 also slides downwards in the recess 6 of the knob 5. After a definite number of turns the pin 4 has descended so far that the projection 7 solid with the pin 4 has reached the stop 8 provided upon the inside of the shell 1 (Fig. 2). On the knob 5 being rotated 60 still further the projection 7 is thrust against the stop 8, with the result that further twisting of the reservoir is prevented. The stops 7 and 8 co-operate equally well, whether the reservoir be twisted in one direction or the other. If the pen is inserted into an ink well or the like and the knob 5 released the reservoir 2 and the knob 5, return to the normal position shown in Fig. 1 under the action of the elasticity of the 70 said reservoir which is thereby filled with ink.

If the elastic reservoir 2 is made of good material, its life is sufficient for practical purposes. However it may become advisable to change the rubber tube constituting the elastic reservoir, in order to be able to use the fountain pen for a further time.

In the form of the pen in which the upper end of the reservoir is not firmly connected to the knob 5 the insertion of a new reservoir is made possible by connecting the plug 9 to the shell by means of a threaded connection. The thread provided for that purpose on the inside of the shell 1 is 80 marked 11. If the plug 9 be screwed out of the shell 1 the shell 1 and the knob 5 are entirely disconnected from the other parts of the fountain pen, and this shell, together with the knob, can therefore be removed 85 from the elastic reservoir 2. The reservoir 2 is then free and can be changed. After a new reservoir has been fixed in position the shell 1 is pushed back again over the reservoir, and the plug 9 is screwed into 90 the shell 1.

A modification of the pen just described is illustrated in Fig. 3. The knob 5 according to Figs. 1 and 2 is substituted by a protective cap 5' which has no connection 100

with the pin 4. After removing the cap 5' the pin 4 is free for being operated by the user. As it will be seen from the drawing the pin may be rotated in both directions as in the case of the constructional form described above but may also be solely pressed downwardly without being turned. Thus it is in the will of the user whether he will fill the reservoir 2 by turning the pin 4 or by pressing down the same like a 10 press-button. In some cases the stops 7 and 8 shown may be dispensed with.

What I claim is:

1. In a fountain pen, an ink reservoir capable of being twisted, a member movable in both directions from the position of rest and operably connected with said reservoir to twist the same, and means for limiting the number of turns in either direction of said movable member.
2. In a fountain pen, a barrel, a flexible reservoir within said barrel, a cap-like member rotatably mounted on the outer end of the barrel and operably connected with the reservoir and rotatable in either direction for twisting the reservoir, and means for limiting the number of turns in either direction of the said cap member, said means comprising a part connected with the reservoir and a part connected with the barrel.
3. A fountain pen in accordance with claim 2, wherein the part on the inner wall of the barrel is in the form of a stop while the part on the reservoir which cooperates with the stop is in the form of a projection which follows the contracting movement of the elastic reservoir when the latter is being twisted and after a definite number of turns in the one or other directions comes to rest against said stop and thereby prevents further twisting of the reservoir.
4. A fountain pen in accordance with claim 2 wherein the cap is provided with a recess substantially rectangular-shaped in cross section which opens towards the interior of the barrel, and a plug of substantially similar shape carried by the adjacent end of the reservoir and slidably and non-rotatably mounted in said recess, substantially as and for the purposes set forth.

In testimony whereof I affix my signature.

HUGO STEIN.
